UNITED STATES PATENT OFFICE.

WALLACE L. GUMM, OF WHITE OAKS, TERRITORY OF NEW MEXICO.

PUMP-ROD COUPLING.

SPECIFICATION forming part of Letters Patent No. 540,834, dated June 11, 1895.

Application filed April 11, 1894. Serial No. 507,163. (No model.)

To all whom it may concern:

Be it known that J. WALLACE L. GUMM, a citizen of the United States, residing at White Oaks, in the county of Lincoln and Territory 5 of New Mexico, have invented certain new and useful Improvements in Pump-Rod Couplings; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to improvements in devices for coupling together the sections of pump rods in a manner to prevent accidental disconnection while in use, and in the operation of inserting and removing the valves.

20 In the majority of wells, especially wells of comparatively great depth a barrel is used, the diameter of which is less than that of the pipe which carries the water to the surface. The lower valve is constructed in such a man-

25 ner as that the plunger valve which is directly secured to the pump rod, may be connected therewith by turning the rod and screwing the valves together, and the whole withdrawn from the barrel and pipe by raising the rod.

30 This arrangement obviates the necessity of removing the pipe when repairs to either valve are needed. The rod is made up of sections secured together and the object of the invention is to prevent these sections from 35 being disconnected or unscrewed from each other while in use, and during the operation of coupling the valves together to remove them, or uncoupling the valves after the same are in place.

40 The invention consists in means for preventing the sections of the rods from turning independently and in the construction of the parts thereof and the relative arrangement and operation of same, all of which will fully 45 and clearly appear from a reading of the following description, taken in connection with the accompanying drawings, which form a part of this specification, and in which—

50 Figure 1 illustrates in perspective view my improved coupling applied. Fig. 2 is a longitudinal sectional view, and Fig. 3 is a cross-section on line xx of Fig. 2.

Referring to the drawings by letter, A denotes one section of a pump rod, and B is the adjacent section, the meeting ends of which 55 are made rectangular in cross section and are provided with holes $c c$. The coupling consists of two members, the upper one d consisting of a rectangular shaped block d' having a recess d^2 in its upper side to receive the 60 end of the section A, and having a socket d^3 centrally arranged and screw threaded as shown. Extending upward from the block are two straps $d^4 d^4$ which in practice confine the lower end of the section A, and have holes 65 $d^5 d^5$ which register with the holes $c c$, and $e e$ are bolts passed through the registering holes and secured by nuts $e' e'$.

The lower member f of the coupling consists of a block f' in the lower side of which is 70 a recess f^2 to receive the upper end of the section B, and extending upward from the upper end of the block is a screw threaded pin f^3 which in practice enters and engages the threaded socket d^3 in the upper member. 75 Depending from the block are two straps $f^4 f^4$ having holes $f^5 f^5$ and which with the bolts $g g$ and nuts $g' g'$ constitute the means for connection with the section B in a manner similar to the connection between the upper 80 member and the section A. The block f' has secured to one of its sides a stop h for a purpose to be explained.

i is a sleeve rectangular in cross section, the inner side conforming in size and shape to the 85 outer side of the blocks. In practice the members are secured respectively to the sections A and B, and the pin entering the socket the parts are turned until the blocks come together. The sleeve which temporarily has 90 been moved upward on the upper member is moved downward over the coupling until the lower side engages the stop. The members are thus held firmly by the sleeve against turning, and consequently the danger of accidental uncoupling is overcome.

In practice all of the sections of the pump rod are connected by my improved coupling, in a manner to insure rigidity throughout. When it is desired to remove the valves for 100 repairs, the rod may be turned to connect the valves without the danger of unscrewing the sections, and as the rod is withdrawn the sections are disconnected by raising the sleeve

and unscrewing the members of the coupling. When the valves are to be replaced the sections are screwed together and the rod lowered, and the latter turned in the opposite direction to disconnect the valves.

The coupling is simple in construction, is cheaply made, and may be easily manipulated.

I claim—

A coupling for the sections of pump rods, consisting of two separable members, the lower one of which comprises a block square in cross section and having in its lower end a rectangular recess for the end of a section of the pump rod, apertured straps integral with said block and connected by bolts and nuts to said section, a threaded pin extending from the upper end of the block, and a stop on one side

of said block; the upper member comprising a block conforming in size and shape to the lower block and having a threaded recess for connection with the pin, and a recess in its upper end for another section of the pump rod, straps integral with said block and having nut and bolt connection with said section, and a square sleeve adapted to be slipped over said blocks when the latter register and to abut against the stop.

In testimony whereof I affix my signature in presence of two witnesses.

WALLACE L. GUMM.
